(57) CLAIM

The ornamental design for a golf cart bra, as shown and described.

DESCRIPTION

FIG. 1 is a perspective view of a golf cart bra showing our new design. The broken lines within FIG. 1 showing the environment are for illustrative purposes only and form no part of the claimed design;

FIG. 2 is a top view of the golf cart bra;

FIG. 3 is a bottom view of the golf cart bra;

FIG. 4 is a first side view of the golf cart bra;

FIG. 5 is a second side view of the golf cart bra;

FIG. 6 is a first end view of the golf cart bra; and,

FIG. 7 is a second end view of the golf cart bra.

The criss-cross pattern is intended to represent fabric and is understood to repeat continuously through the circumscribed area.
